(57) **CLAIM**

The ornamental design for a multi-directional vent limiter, as shown and described.

DESCRIPTION

FIG. 1 is a front-top-right perspective view of a multi-directional vent limiter showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front-top-right perspective view thereof, showing the design article in a state of use.

The broken lines in the figures illustrate portions of the multi-directional vent limiter that form no part of the claimed design.
